UNITED STATES PATENT OFFICE.

EVERETT L. THOMPSON, OF NEW YORK, N. Y.

ALARM VALVE AND SYSTEM.

SPECIFICATION forming part of Letters Patent No. 743,049, dated November 3, 1903.

Application filed May 27, 1903. Serial No. 158,927. (No model.)

To all whom it may concern:

Be it known that I, EVERETT L. THOMPSON, a citizen of the United States, and a resident of the borough of Brooklyn, city of New York, county of Kings, and State of New York, have invented certain new and useful Improvements in Automatic Sprinkler-Alarm Devices, of which the following is a specification, taken in connection with the accompanying drawings, which form a part of the same.

This invention relates to automatic sprinkler-alarm devices, such as may be used in connection with the ordinary automatic sprinkler systems for giving an alarm in case of fire or the opening of the sprinkler systems.

In the accompanying drawings, in which the same reference characters refer to similar parts in the several figures, Figure 1 is a cross-section of one form of valve and alarm device embodying this invention. Fig. 2 is a cross-section of a modified form. Fig. 3 is an elevation, partly in section, of an automatic sprinkler system containing a form of this alarm device.

In the accompanying drawings, which represent embodiments of this invention, the supply-pipe A is connected with a distributing system, which comprises the distributing-pipes B, arranged throughout a building or other structure, and suitable sprinkler-heads, such as b, to automatically operate in the event of fire. The supply-pipe is preferably formed with means for maintaining a difference of pressure in the pipe on the commencement of a flow therethrough, and this means may take the form of a check-valve D, (indicated in Fig. 3,) weighted so as to give the desired pressure per square inch, which operates with the seat d in the valve-casing C. The alarm device is preferably directly connected with the supply-pipe adjacent the valve or other means for maintaining difference of pressure therein.

In the preferred embodiment of this invention (indicated in Fig. 1) the jet device for actuating the alarm is shown as axially mounted within the supply-pipe A, this jet device comprising the jet-pipe 1, supported by a suitable bridge c and containing the opposed nozzles 2 and 3, the nozzles being preferably given the tapering form indicated, so that

opposed contracting passages are formed in this way. Between the two nozzles and the inner walls of the jet-pipe is formed an exhaust-chamber 4, with which the exhaust-tube 5 connects. These coöperating nozzles constitute the jet device E. The check-valve D is indicated in this case as mounted upon the jet-pipe 1 and is guided in this manner so as to coöperate with the seat d. The spring d' may be used to normally hold the check-valve upon its seat and also to maintain a difference of pressure in the supply-pipe at this point when a flow up through the pipe commences.

When one or more sprinklers in the distributing system open and a flow of water takes place up through the supply-pipe, the difference of pressure maintained at the valve D will cause a stream of water to be forced through the jet device. The velocity through the opposed nozzles 2 and 3 causes a diminution of pressure in the exhaust-chamber 4, so as to operate an alarm connected with the exhaust-tube 5. This action of the jet device depends upon the velocity of water passing through the same, and is therefore comparatively undisturbed by the action of water-hammer in the pipes or other accidental variations in pressure. Furthermore, since the jet device provides a passage at all times around the valve water may pass through this device and operate to equalize the pressure without actuating the alarm device, since pulsations are not sufficient in amount nor sufficiently continuous in action to cause any exhaust or substantial loss of pressure in the exhaust-tube 5. In the event of water-hammer sufficient to lift the valve D from its seat this lifting of the valve would not necessarily operate the jet device or the alarm connected therewith.

The diaphragm-casing 7 may be connected by the exhaust-tube 5 with the jet device, as seen in Fig. 1, and this casing may have the diaphragm 10 clamped between its upper and lower halves 8 and 9. The pipe 15 is indicated as connecting with the supply-pipe below the valve, so that this pressure is exerted upon the under surface of the diaphragm 10. Upon the diaphragm the post 11 is mounted, connected with which is the valve 12, which is pivoted or otherwise suitably mounted at

13, so that when the diaphragm is in its normal position the valve is seated upon the open end of the pipe 14, which may be connected with any suitable alarm mechanism. 5 As seen in Fig. 3, this pipe may be connected with an electric and also with a mechanical alarm, the electric alarm comprising the chamber 16, in which the diaphragm 17 is mounted, so that it may be lifted into electrical contact with the contact-points 18 18, the connections 19 19, secured to these contact-points, operating an electric bell 20 in an obvious manner. The water-motor 21 may have any desired form and is indicated as having a 10 chamber 16, connected with the pipe 14. The shaft 22 of the motor has the hammer 23 mounted on the end of the same, so as to engage the bell 24.

When a suitable reduction of pressure 20 takes place in the exhaust-tube 5, the diaphragm 10 is thereupon lifted, and the valve 12 is thus lifted from its seat on the end of the pipe 14. The water is under these conditions allowed to enter the pipe 14 and serves 25 to operate the mechanical alarm, as indicated, and also serves to raise the diaphragm 17, so as to close the circuit of the electric alarm.

It is not necessary, of course, to arrange the 30 jet device in the stand-pipe itself, as is indicated in Fig. 1. In Fig. 2 a modified construction is indicated, in which the jet device is located in a by-pass. The nozzles of the jet device are directly connected by the pipes H 35 H with the supply-pipe on either side of the check-valve D, suitably weighted to give the desired pressure per square inch. These pipes which form the by-pass give an open connection which allows a free flow of water through 40 the jet device, the operation of which and its connection with the alarm being similar to what has been described.

The jet device may also be located at a point exterior to the supply-pipe, as is indicated in 45 Fig. 3. The air-chamber G is indicated in that instance as connected by the pipe F with the supply-pipe above the weighted check-valve D. The jet device E is located in this pipe F, as indicated. Under these circumstances 50 when the system is filled with water the water rises through the pipe F and partly fills the chamber G, compressing the air therein. When the sprinklers open in the distributing system, the compressed air in the chamber G 55 forces the water out of this chamber and through the jet device, thus creating a loss of pressure in the chamber 4 and exhaust-pipe 5 and actuating the alarm mechanism in the manner described. The pipe 15 is in this 60 form of apparatus preferably connected with the pipe F between the jet device E and the chamber G. Water-hammer and other variations of pressure in the system will not under these circumstances operate the alarm, 65 the jet device equalizing these momentary variations in pressure.

This invention may be used in connection

with any type of valve located in the supply-pipe or may be used outside of the supply-pipe and irrespective of the type of valve in 70 the supply-pipe. In some cases also the valve may be entirely omitted from the supply-pipe. Furthermore, the structure of the jet itself may be modified, the exact form not being essential so long as it is arranged in such manner as to operate in the event of a flow in the 75 distributing system to cause a loss of pressure in the exhaust-pipe connected to the alarm mechanism.

Many modifications may be made by those 80 familiar with this art in the form, size, proportion, and numbers of parts of this apparatus. Parts of the same may be used in connection with other devices and parts may be employed without using all of the same without departing from the spirit of this invention 85 or losing the advantages of the same. I do not therefore desire to be limited to the disclosure which has been made in this case; but what I claim as new, and what I desire to secure by Letters Patent, is set forth in the appended claims.

What I claim as new, and desire to secure by Letters Patent, is—

1. In automatic sprinklers, a distributing 95 system, a supply-pipe connected therewith, a spring-pressed valve in said supply-pipe, a jet device comprising opposing nozzles and an exhaust-opening, said nozzles being directly connected with said supply-pipe on 100 either side of said valve, an alarm and a tube connecting said alarm and said exhaust-opening.

2. In automatic sprinklers, a distributing system, a supply-pipe connected therewith, a 105 check-valve in said supply-pipe, a jet device comprising opposed nozzles, one of which is directly connected with said supply-pipe adjacent said valve, an alarm, and an exhaust-tube connecting said alarm and said jet device. 110

3. In automatic sprinklers, a distributing system, a supply-pipe connected therewith, a valve in said supply-pipe, to maintain a difference of pressure on either side of the same 115 on the commencement of flow through said pipe, a jet device having a direct open connection with said supply-pipe adjacent said valve, an alarm, and a tube connecting said alarm with said jet device to actuate said 120 alarm in the event of a flow in said distributing system.

4. In automatic sprinklers, a distributing system, a supply-pipe connected therewith, means to maintain a difference of pressure in 125 said pipe on the commencement of flow therethrough, a jet device having a direct open connection with said supply-pipe adjacent said means, an alarm, and a tube connecting said alarm with said jet device to actuate said 130 alarm in the event of a flow in said distributing system.

5. In automatic sprinklers, a distributing system, a supply-pipe connected therewith, a

jet device comprising opposed nozzles directly connected with said supply-pipe, an alarm and an exhaust-tube connecting said alarm and said jet device to operate said alarm in the event of a flow in said distributing system.

5 6. In automatic sprinklers, a supply-pipe, a jet-pipe in said supply-pipe having a nozzle mounted therein, a check-valve in said supply-pipe inclosing said jet-pipe and an exhaust-tube communicating with said jet-pipe adjacent said nozzle to be connected with an alarm.

10 7. In automatic sprinklers, a supply-pipe, a jet-pipe in said supply-pipe, a valve in said supply-pipe and mounted to move upon said jet-pipe, opposed adjacent nozzles in said jet-pipe forming an exhaust-opening between the same and an exhaust-tube to connect said exhaust-opening with an alarm.

15 8. In automatic sprinklers, a jet device comprising two adjacent opposed nozzles, an exhaust-opening adjacent said nozzles, one of said nozzles being of larger diameter than the other, an alarm, and a tube connecting said exhaust-opening with said alarm.

20 9. In automatic sprinklers, a jet device comprising opposed nozzles, an alarm and an exhaust-tube connecting said alarm and said jet device adjacent said nozzles.

25 10. In automatic sprinklers, a jet device comprising opposed contracting passages, an alarm, and an exhaust-tube connecting said alarm and the contracted portion of said passages in said jet device.

30 11. In automatic sprinklers, a distributing system, a supply-pipe connected therewith, a jet device comprising opposed contracting passages directly connected with said supply-pipe, an alarm, and an exhaust-tube connecting said alarm and the contracted portion of said passages to operate said alarm in the event of a flow in said distributing system.

35 12. In automatic sprinklers, a distributing system, a supply-pipe connected therewith, means to maintain a difference of pressure in said supply-pipe on the commencement of flow through said pipe, a jet device comprising opposed contracting passages directly connected with said supply-pipe adjacent said

means, an alarm, and a tube connecting said alarm with said jet device to actuate said alarm in the event of a flow in said distributing system.

40 13. In automatic sprinklers, a supply-pipe, a jet-pipe in said supply-pipe having a contracting passage therein, a check-valve in said supply-pipe inclosing said jet-pipe and an exhaust-tube communicating with the contracted portion of said passage to be connected with an alarm.

45 14. In automatic sprinklers, a distributing system, a supply-pipe connected therewith, means to maintain a difference of pressure in said pipe on the commencement of flow therethrough, a jet device comprising a contracting passage having a direct open connection with said supply-pipe adjacent said means, an alarm and an exhaust-tube connecting said alarm with said jet device to actuate said alarm in the event of a flow in said distributing system.

50 15. In automatic sprinklers, a distributing system, a supply-pipe connected therewith, a valve in said supply-pipe to maintain a difference in pressure on either side of the same on the commencement of flow through said pipe, a jet device comprising an exhaust-opening and a jet directly connected with said supply-pipe on either side of said valve, an alarm and an exhaust-tube connecting said alarm and said exhaust-opening to actuate said alarm in the event of a flow in said distributing system.

55 16. In automatic sprinklers, a distributing system, a supply-pipe connected therewith, means to maintain a difference of pressure in said pipe upon the commencement of flow therethrough, a jet device comprising an exhaust-opening and a contracted passage directly connected with said supply-pipe on either side of said means, an alarm and an exhaust-tube connecting said alarm with said exhaust-opening to actuate said alarm in the event of a flow in said distributing system.
